CLAIM

The ornamental design for a lavatory, as shown and described.

DESCRIPTION

FIG. 1 is a top, front perspective view of a lavatory showing my new design;

FIG. 2 is a top plan view thereof;

FIG. 3 is a front elevational view thereof;

FIG. 4 is a rear elevational view thereof;

FIG. 5 is a right side elevational view thereof, the left side being a mirror image of the right side shown; and

FIG. 6 is a bottom plan view thereof.

Fig. 2.

Fig. 3.

Fig. 4.
